UNITED STATES PATENT OFFICE

2,449,378

SYSTEM FOR DISPENSING A LIQUEFIED GAS

Odd A. Hansen, Kenmore, N. Y., assignor to The Linde Air Products Company, New York, N. Y., a corporation of Ohio

Application July 25, 1941, Serial No. 403,935

9 Claims. (Cl. 62—1)

1

This invention relates to a system for dispensing and/or delivering a liquefied gas, and particularly to a portable system for delivering a liquefied gas which has a boiling point temperature at atmospheric pressure materially below 273° K., such as liquid oxygen.

The invention has for its object generally an improved construction and arrangement of parts whereby the liquefied gas may be simply and quickly transferred by pumping from a portable container to a liquid phase receiver.

More particularly, the invention has for its object an improved arrangement of a container on a transport vehicle, together with a pumping device for transferring liquid oxygen and the like from the portable container to a receiving container at a consuming installation, which latter container may be under pressure.

Another object of the invention is to provide a liquid oxygen dispensing system which provides a source of supply and employs but a single pumping device to effect delivery of the liquid oxygen and is of a character such that the whole system including the pumping device may be mounted on a truck or other suitable vehicle, whereby deliveries of the liquid oxygen may be made directly to a liquid receiving container at a consuming installation.

Still another object of the invention is to provide a system of the character indicated with a connection of a character such that the liquid to be pumped which would otherwise be delivered to the pump in a nearly boiling state may be quickly and effectually subcooled and readily pumped directly into a liquid receiving container while the latter is under pressure and in service.

Other objects of the invention will in part be obvious and will in part appear hereinafter.

The invention accordingly comprises the features of construction, combination of elements, and arrangement of parts, which will be exemplified in the construction hereinafter set forth, and the scope of the invention will be indicated in the claims.

For a fuller understanding of the nature and objects of the invention reference should be had to the following detailed description taken in connection with the accompanying drawing, in which:

Fig. 1 is a view, partly in section and partly in elevation, showing a system for transferring liquid oxygen from a portable container to a receiving container in accordance with the invention; and

Fig. 2 is a view, partly in elevation and partly

2

in section, the plane of section being indicated by the line 2—2 on Fig. 1, showing details of a turbine type pumping device which may be used in the combination shown in Fig. 1.

5 Referring now to the drawing, and particularly to Fig. 1, 10 denotes a wheeled chassis of a motor vehicle powered by suitable means, such as an internal combustion motor. Such chassis here supports a transport container, shown as comprising a casing 11 and a liquid holding vessel 12, in order to provide a suitable space 13 for insulating purposes, for example, one which may be filled with powdered insulating material, such as magnesium carbonate. The transport container is also shown provided with a closable vent 14.

Associated with the transport container is a suitable mechanical liquid transferring means or pumping device, such as a turbine pump 15, which

20 may have one or more stages, depending on the kind of service it is required to give. Such pump is preferably of the character disclosed in co-pending application, Serial No. 345,308, filed July 13, 1940 in the name of O. A. Hansen, which issued

25 February 1, 1944, as Patent No. 2,340,747, and is provided with suitable driving means, for example, with an electric motor, shown at M in Fig. 2. The power for such motor is had from any convenient source, for example, from a power

30 line run from an outlet or plug-in receptacle at the consuming installation. It is also contemplated using a power take-off on the torque shaft of the motor vehicle as the source of driving power, as set forth in copending application,

35 Serial No. 369,023, filed December 7, 1940, in the name of O. A. Hansen, which issued November 28, 1944, as Patent No. 2,363,960.

The pump 15 has a liquid supply connection 16 connected to withdraw liquid from a point substantially at the bottom of the vessel 12 and convey it to the inlet of pump 15. A connection 18 is also provided and arranged to convey away the discharge from the outlet of the pump; a flexible portion 18' being attached by means of a suitable coupling. Connections 18—18' are arranged, when at a consuming installation, to be connected to a liquid inlet connection 19 of a suitable liquid receiving or storage container, here shown as comprising a pressure vessel 20 in a casing 22, which is disposed in spaced relation to the pressure vessel for insulating purposes.

The connection 19 has a valve 19* for controlling the passage of liquid phase. There is preferably included a valve controlled gas phase branch 19' 55 whereby gas phase may be withdrawn and equal-

ization effected between the containers 12 and 20 by way of connections 18, 18', and 19', as herein-after explained. Vessel 12 preferably has no basket but in order that its wall may withstand equalization pressures, it is made relatively thick, so as to have the desired strength.

The liquid receiving or storage container is part of a system arranged to supply the consuming apparatus with gaseous or vaporized liquid oxygen under a desired pressure. The pressure vessel 20 here employed preferably has a spaced inner basket 21 for holding the liquid, and reducing the amount of heat otherwise transferred thereto by conduction. The wall of vessel 20 is made sufficiently thick to withstand the operating pressure, for example, a pressure of 150 lbs. per square inch gauge. The vessel 20 is connected to discharge into suitable heating and liquid vaporizing devices which are operatively associated therewith, the arrangement comprising a so-called "cold converter system." Such connections are shown as comprising a gas phase withdrawal connection 24 leading from the gas space of the vessel 20 and discharging into a heating coil 25 from which the heated gas passes to a consuming device. Connection 24 is preferably valve controlled, and is shown with such at 24'. A liquid phase withdrawal connection 26 is also provided, which leads from a point relatively close to the bottom of the liquid holding vessel and discharges into a heating coil 27. The discharge from the coil 27 is led through a reentrant connection 28 which traverses a liquid column or side conduit 29 that is adjacent vessel 20; an automatic flow controller, such as the regulator shown at 23, being preferably introduced in connection 28 at a suitable point. The conduit 29 is connected to the interior of vessel 20, or more exactly to that of the basket 21, at its ends at points both above and below the normal liquid level in the manner taught in United States Letters Patent No. 1,950,353, issued in the name of L. I. Dana on March 6, 1934. The liquid in the column becomes heated and serves to accelerate the withdrawal of liquid from the container and to hasten the vaporization of oxygen in the cold converter system. The connection 28 leads out again to the exterior of the container to a place of use and preferably includes another heating coil 30.

Suitable heating media are supplied for heating the coils 25, 27, and 30, the three comprising the heating means here associated with the receiving container and denoted generally at H.

To achieve priming of the pump 15, a connection 31 having a valve 32 is provided and arranged to lead from the outlet of the pump to the gas space of the vessel 12.

The system of the present invention is preferably arranged to effect the ready transfer of liquid phase from the vessel 12 to the vessel 20 without blowdown losses. To this end, a gas phase transfer connection is additionally provided for the vessels. The arrangement preferably employed comprises a connection 35 leading from the gas space of the vessel 20 to that of vessel 12; such connection having a valve 36 therein and terminated by a coupling to which a second flexible connection 35' may be attached for coupling to an extension 31' of the connection 31. Extension 31' is provided with a valve 37 and terminates in a coupling adapted for the attachment of the flexible connection 35'.

In operation, when it is desired to effect a

transfer of liquid phase from the transport container to a consuming installation, i. e., from vessels 12 to 20 in the system illustrated, the apparatus provided enables the transfer to be effected by any one of three possible methods, as follows:

Method I.—When the transport container has reached the consuming installation and service connections established, as indicated in the drawing, the step of equalizing pressures between containers 12 and 20 is practiced by opening valves 36 and 37; the valve at 14 being closed. In this operation the pressure in vessel 12 may rise sufficiently to change adiabatically the condition of the liquid in vessel 12 whereby the liquid is to a substantial degree in a subcooled condition. Upon completion of equalization of pressures valves 36 and 37 are closed and the step of pump priming is practiced by starting pump 15 and opening valves 16' and 32. As soon as liquid begins to pass, the valve at 32 is closed and that at 19' opened. The step of transferring liquid from vessel 12 to vessel 20 then follows; the pressure in vessel 20 gradually building up the while. When a desired quantity of liquid has been transferred, the valves 16' and 19' are closed and the transport container disconnected. This method is seen to impose a gradually increasing amount of work on the pump 15 when transferring liquid.

30 In this method, it is seen that an equalization of pressure may be preliminarily effected without opening valves 36 and 37. The valve in branch 19' is opened instead; also the valve 16' is opened. The gas phase from vessel 20 is seen then to pass into vessel 12 by way of connection 16, a portion of the gas phase thus transferred being liquefied in the liquid phase in vessel 12.

Method II.—This is an alternative procedure that may be practiced when service connections have been established, as indicated in the drawing. The first step is that of equalization which is effected by opening valves 36 and 37. When equalization has been accomplished, the step of pump priming is practiced without closing valves 36 and 37. When liquid begins to pass, the valve 19' is opened, the valve 32 being closed at the same time so that the step of transferring liquid takes place. Valves 36 and 37 are continued open while the transfer of liquid continues. In this second method, there is substantially no concurrent increase in the work of the pump, as takes place in the first method. Instead, there is continuous equalization of the pressures in vessels 12 and 20.

55 It is also seen that where the step of equalization has been practiced by effecting the gas phase transfer, the pressure in the vessel 12 may rise sufficiently, similarly as noted in connection with Method I, to result in a substantial degree of subcooling. As a result, the pump 15 has a greater capacity and liquid transfer from the vessel 12 to the vessel 20 is effected in a relatively short space of time.

60 A variation in Method II having distinct advantages comprises an operation in which the initial equalization of pressures is effected through conduit 19' by opening the valve therein, and then after pump priming has been effected and the liquid begins to pass and line 19' closed off, maintaining equilibrium between vessels 12 and 20 through opening valves 36 and 37. The required head of the pump is low and by effecting equalization by passing gas from vessel 20

through the liquid phase of vessel 12 the final pressure in the latter is kept relatively low.

Method III.—By this method, the step of equalization is omitted and the gas phase transfer connection by way of the conduits 35, 35' and 31' is not established. Here the first step is that of pump priming after which valve 32 is closed and that at 19° opened, in order to effect the step of transferring liquid from vessel 12 to vessel 20. In this method the pump 15 is required to operate against a relatively high head of pressure, and hence may have two or more stages, as pointed out above.

Under the conditions indicated for Method III, the gas servicing and vaporization take place continuously, and the storage container operates as a cold converter and need not be stopped while liquid is being transferred, as the pump 15 here has capacity to operate against a substantial head of pressure.

Since certain changes may be made in the above construction and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent is:

1. In a system for dispensing a liquefied gas having a boiling point temperature at atmospheric pressure materially below 273° K., the combination with a supply container having a space for holding gas and liquid therein and closable to the atmosphere, of consuming apparatus provided with a liquid receiving container having a space for holding gas and liquid therein and normally under pressure, valved means for establishing both gas and liquid phase transfer connections between the gas and liquid holding portions of said spaces in said containers, a rotary type pump in said liquid phase transfer connections, priming means for said rotary type pump leading to the gas space of said supply container, and means for establishing an additional transfer passage between the gas holding space of said receiving container and the liquid holding space of said supply container.

2. In a system for dispensing liquid oxygen and the like, the combination with a transport container having a space for holding gas and liquid therein and closable to the atmosphere, of consuming apparatus provided with a liquid receiving container having a space for holding gas and liquid therein and normally under pressure, valved means for establishing both gas and liquid phase transfer connections between the gas and liquid holding portions of said spaces in said containers, a turbine type liquid oxygen pump in said liquid phase transfer connections, priming means comprising a conduit leading from the outlet of said pump to the gas space of said transport container, and a valved branch on said liquid receiving container for establishing an additional gas phase transfer passage between the gas holding space of said receiving container and the liquid holding space of said supply container.

3. A method of delivering liquid oxygen and the like from a supply container adapted to be closed to the atmosphere and provided with a liquid transfer pump into a liquid receiving container of a cold converter system normally under pressure, which comprises the steps, in combination,

of establishing both gas and liquid phase transfer connections between the gas and liquid holding spaces of said containers, equalizing the pressures in said containers, closing the gas phase transfer connections, priming the pump, and transferring liquid to the receiving container against the rising head of pressure therein.

4. A method of delivering liquid oxygen and the like from a supply container adapted to be closed to the atmosphere and provided with a liquid transfer pump into a liquid receiving container of a cold converter system normally under pressure, which comprises the steps, in combination, of establishing both gas and liquid phase transfer connections between the gas and liquid holding spaces of said containers, equalizing the pressures in said containers, said equalizing including passing at least a portion of the gas pipe phase through the liquid phase in said supply container, priming the pump, and thereafter transferring liquid to the receiving container.

5. In a method of dispensing liquid oxygen by pumping from a transport container closable to the atmosphere to a liquid receiving container in a cold converter system, the steps, in combination, of establishing both gas and liquid transfer connections between the gas and liquid holding spaces in said containers when said transport container is closed to the atmosphere, equalizing the pressures on the liquid in said containers whereby the pressure on the liquid in said transport container may be substantially adiabatically increased and the liquid to be supplied to the liquid transfer pump in the liquid phase transfer connections effectually subcooled, priming the liquid transfer pump, and thereafter transferring liquid from said transport container to said receiving container while maintaining communication of said receiving container with the service withdrawal lines of said converter system to provide thereby an auxiliary gas space to supplement the reduced gas space of said receiving container resulting from the filling operation.

6. A method of delivering liquid oxygen and the like from a supply container adapted to be closed to the atmosphere into a liquid receiving container normally under pressure, which comprises the steps, in combination, of equalizing the pressures in the two containers by passing gas from said receiving container through the liquid phase in said supply container, and thereafter transferring liquid to the said receiving container while maintaining said containers independent of each other as to pressure.

7. A method of delivering liquid oxygen and the like by means of a power pump from a supply container into a liquid receiving container normally under pressure and open to a service dispensing pipeline, which comprises the steps of priming the pump by directing initially the discharge therefrom to the supply container, and thereafter transferring liquid by said pump to the receiving container while maintaining said two containers independent of each other as to pressure, said liquid being delivered to said container at a pressure as determined by that in said pipeline.

8. A method of dispensing from a supply container a liquefied gas having a boiling point temperature at atmospheric pressure below 233° K., comprising pumping the liquid therefrom to a receiving container while maintaining said containers independent of each other as to pressure, and withdrawing gas material from said receiving container and passing it through a heating coil

as required for use, said operations of pumping and withdrawal being performed in part at least simultaneously and the delivery pressure of said pump being determined by that in the withdrawal line.

9. A method of dispensing from a supply container a liquefied gas having a boiling point temperature at atmospheric pressure below 233° K., comprising pumping the liquid therefrom to a receiving container while maintaining said containers independent of each other as to pressure, and withdrawing gas material from said receiving container through vaporizing and heating means as required for use, said receiver being open to the withdrawal system during said pumping operations and affording a gas capacity to compensate for the introduction of the liquid to said receiver, the delivery pressure of said pump being determined by that in said system.
